[57] CLAIM

The ornamental design for chair, as shown and described.

DESCRIPTION

FIG. 1 is a perspective view taken from the top, front and right side of a chair embodying my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being the mirror image of the right side shown;

FIG. 7 is a perspective view taken from the top, front and right side of a second embodiment of my new design;

FIG. 8 is a front elevational view thereof;

FIG. 9 is a rear elevational view thereof;

FIG. 10 is a top plan view thereof;

FIG. 11 is a bottom plan view thereof; and,

FIG. 12 is a right side elevational view thereof, the left side elevational view being the mirror image of the right side shown.

FIGS. 1 and 7 have been shown on an enlarged scale.
